(57) **CLAIM**

The ornamental design for a display panel connector, as shown and described.

DESCRIPTION

FIG. 1 is a front perspective view of a display panel connector showing our new design;

FIG. 2 is a front view thereof;

FIG. 3 is a rear view thereof;

FIG. 4 is a left side view thereof;

FIG. 5 is a right side view thereof;

FIG. 6 is a top side view thereof; and,

FIG. 7 is a bottom side view thereof.

The dash-dash-dash broken lines in the Figures are for the purpose of illustrating unclaimed portions of the display panel connector and form no part of the claimed design.

The dash-dot-dash broken lines are boundary lines. It is understood that the claimed design extends to the boundary lines but the boundary lines form no part of the claimed design. The shade lines in the Figures show contour and not surface ornamentation.
